UNITED STATES PATENT OFFICE.

JAMES CAMPO, OF STAFFORD SPRINGS, CONNECTICUT.

BOTTLE-STOPPER.

1,178,903.

Specification of Letters Patent. Patented Apr. 11, 1916.

Application filed April 26, 1915. Serial No. 23,809.

To all whom it may concern:

Be it known that I, JAMES CAMPO, a citizen of Italy, residing at Stafford Springs, in the county of Tolland and State of Connecticut, have invented certain new and useful Improvements in Bottle-Stoppers, of which the following is a specification.

My invention relates to an improved bottle stopper, and is particularly adapted for bottles containing charged or effervescent liquid to be dispensed from time to time.

At present, charged liquids are generally supplied in comparatively small bottles, because of the difficulty of preventing the escape of gas from large bottles after the receptacle has once been opened. This applies to all kinds of charged liquids except selters and the like, the bottles containing which are provided with expensive discharge caps. Those liquids which are bottled in receptacles that are closed by the ordinary crown seals must be consumed practically as soon as the bottle is opened in order to avoid the deterioration above suggested.

The principal object of my invention is to provide a form of stopper which is especially designed for use in connection with bottles closed with crown seals, the said stopper protecting the contents of the bottle after the latter has been opened, the liquid retaining its gas charge for a practically indefinite time.

Two forms of the invention are illustratively exemplified in the accompanying drawing, in which—

Figure 1 is a vertical sectional view of the preferred form of stopper applied to a bottle, a fragment of the latter being shown; Fig. 2 is a side elevational view of the stopper shown in Fig. 1; Fig. 3 is a perspective view of a metal cap which I prefer to place over the bottle mouth and upon which my improved stopper is superimposed; Fig. 4 is a similar view to Fig. 1 of a modified form of the invention; and Fig. 5 is a vertical sectional view on the line 5—5 of Fig. 4.

Referring to the drawing, and more particularly to Figs. 1 to 3 thereof, 10 denotes the neck of a bottle, the mouth of which is provided with an ordinary crown seal 11. This seal usually consists of a metal disk having its edge crimped down over the outer side of the flange 12 of the bottle neck.

The improved stopper proper comprises a

resilient cushion 13, preferably of rubber, and approximately the shape of the bottle neck. Superimposed on the cushion 13 is a metal neck 14 having the depending sleeve 60 or skirt 15 which envelops the cushion 13 and is provided with a clamp 16. The clamp pivotally supports, at 17, a cam lever 18 by means of which the clamp may be secured to and freed from the bottle neck. 65 The interior of the neck 14 is threaded to receive a correspondingly threaded depending sleeve 19 formed integrally with the stopper head 20. The neck 19 is hollow and communicates with the outlet 21 formed 70 laterally in the head 20. Also removably secured to the lower end of the neck 19, as by means of screw threads, is a cutter 22 which may be of annular or prismatic or other suitable form, as preferred. The cutter 75 normally projects below the lower plane of the upper horizontally disposed portion of the rubber cushion 13, and above the cutter is a screen 23 to prevent any solid particles from passing out of the bottle through 80 the outlet 21.

The head 20 is provided with a depending flange 24 acting as a stop and seat for a valve 25 which is normally pressed against the seat 24 by a coiled spring 26, one end of which spring rests against the screen 23 and the other end of which engages said valve 25. Threaded into the valve 25 is a valve rod or stem 27 which projects up into the head 20 and passes through suitable packing 90 28. The upper end of the valve stem 27 is pivotally connected to an operating lever 29 which may be elevated to depress the valve 25 and permit liquid to issue through the outlet 21. 95

Fig. 3 discloses a metallic cap which I prefer to place over the sealed bottle before applying my improved stopper, this cap serving to prevent injury to the rubber cushion 13 by any sharp edges which may be produced in the crown seal when the latter is disrupted by the cutter 22. This metallic cap is practically a ring 30 having a depending slotted flange 31 which engages the flange 12 of the bottle neck. 105

In the modified form of invention shown in Fig. 4, the structure is substantially similar to that of the preferred form, except that the spring 26 of Fig. 1 is completely housed within the stopper head. In Fig. 110 4, I may, if desired, dispense with the cutter shown in the preferred form, and disrupt

the crown seal by means of a knife or other suitable instrument.

Referring to Fig. 4, 10^a denotes the bottle neck having the external flange 12^a. 13^a 5 denotes the rubber cushion embraced by the sleeve 15^a depending from the head 20^a of the stopper. 21^a is the stopper outlet; 24^a denotes the depending flange within the head against which the valve 25^a seats. 27^a 10 is the valve rod or stem which projects up into the head 20^a and is surrounded near its upper portion by the spring 26^a contained in a suitable bore 40 in the stopper head. 29^a is the operating lever for the 15 valve. 16^a is the clamp, and 18^a the clamp lever carried on the pivot 17^a for securing the stopper to and releasing it from the bottle.

The operation of the device may be 20 briefly described as follows:—I first place the ring 30 over the crown 11 of the bottle 10. I then unscrew the head 20 and sleeve 19 together with the cutter 22 from the neck 14, and then place the neck 14 with its 25 contained rubber cushion and attached clamp 16 over the bottle head. The clamp lever 18 is then operated to clamp the cushion and sleeve 15 about the bottle head. Thereafter the head and cutter are screwed into 30 place, by which action the cutter disrupts the crown seal 11, and as the cutter is worked down the rubber cushion 13 may be correspondingly moved down on the bottle head by alternately opening and closing the 35 clamp 16 until the parts are tightly in position. The escape of charged liquid from the bottle is rendered impossible by the protective action of the cutter. It will be noted that as the latter is moved down it is interposed between the edge of the disrupted seal 11, and the bottle mouth thus itself forming a seal.

When any liquid is to be discharged, the 40 operating lever 29 is depressed until the desired amount of liquid is dispensed. Upon release of the operating lever the valve 25 which has been depressed by the depression of the lever, is automatically reseated against the flange 24 and the bottle 45 is thus again stoppered. In this manner all accidental escape of gas or discharge of fluid is avoided.

Having thus described my invention, what I claim is:—

55 1. In a stopper for receptacles designed to contain charged liquids, the combination

of a head adapted to be placed over the receptacle mouth and having a passage therethrough in direct communication with the interior of the receptacle, said head also 60 having a discharge outlet, a valve seat within said head, a valve operable within said head and in position to have the pressure within the bottle coöperate in holding said valve to said seat, means for unseating said 65 valve, means within the head for disrupting a bottle stopper, a flexible skirt depending from said head and adapted to embrace the bottle neck; and means for tightly clamping said skirt to said receptacle. 70

2. In a stopper for receptacles designed to contain charged liquids, the combination of a head adapted to be placed over the receptacle mouth and having a passage 75 therethrough in direct communication with the interior of the receptacle, said head also having a discharge outlet, a valve seat within said head, a valve operable within said head and in position to have the pressure within the bottle coöperate in holding 80 said valve to said seat, means for unseating said valve, a spring for initially pressing said valve to said seat, means within the head for disrupting a bottle stopper, a flexible skirt depending from said head and 85 adapted to embrace the bottle neck; and means for tightly clamping said skirt to said receptacle. 90

3. In a stopper for receptacles designed to contain charged liquids, the combination 95 of a head adapted to be placed over the receptacle mouth and having a passage therethrough in direct communication with the interior of the receptacle, said head also having a discharge outlet, a valve seat within 100 said head, a valve operable within said head and in position to have the pressure within the bottle coöperate in holding said valve to said seat, means for unseating said valve, means within the head for disrupting 105 a bottle stopper, a flexible skirt depending from the head and adapted to embrace the bottle neck, means for tightly clamping said skirt to said receptacle, and cushioning means interposed between the stopper and the receptacle neck.

In testimony whereof I have affixed my signature in presence of two witnesses.

JAMES CAMPO.
